UNITED STATES PATENT OFFICE.

WILLIS H. PAIGE, OF KANSAS CITY, MISSOURI.

DESIGN FOR A PEN-RACK AND PAPER-CLIP HOLDER.

41,026.

Specification for Design.

Patented Dec. 6, 1910.

Application filed August 8, 1910. Serial No. 576,265. Term of patent 7 years.

To all whom it may concern:

Be it known that I, WILLIS H. PAIGE, a citizen of the United States, and residing at Kansas City, in the county of Jackson and State of Missouri, have invented a new, original, and ornamental Design for a Pen-Rack and Paper-Clip Holder, of which the following is a specification, reference being had to the accompanying drawing, forming part thereof.

The figure is a perspective view of a holder, showing my new design.

I claim:

The ornamental design for a pen rack and paper clip holder, as shown.

WILLIS H. PAIGE.
